PRESSURE MECHANISM FOR THE ROLLERS
OF SPINNING AND LIKE MACHINES

Ramon Balmes Solanas, Santa Coloma de Cervello, Spain, assignor to Estirajes Balmes, S. A., Barcelona, Spain

Application October 18, 1951, Serial No. 251,843

Claims priority, application Spain
October 25, 1950

6 Claims. (Cl. 19—135)

1

In the drawing mechanisms of spinning frames or preparation machines, pressure has to be exerted upon the top rollers of the various pairs of rollers, with a view to their conveniently controlling the fibres of the roving or sliver of fibres that is being worked.

To this end a great many mechanisms have been devised, in which the pressure is obtained by the action of weights or springs, and is transmitted by means of levers and draw-rods to the saddles which weight the top rollers of the various pairs of rollers. The weights and springs, and also the levers, are generally arranged beneath the roller stands or pedestals and the bottom rollers or fluted rollers of the drawing mechanism, and the draw-rods generally pass through between these rollers to transmit the pressure to hooks or saddles, which weigh down the top rollers.

Those members which remain interposed between the table of the machine and the rollers of the drawing mechanism constitute a constant hindrance which hampers the work of the operatives, and they also make it difficult and complicated to unload the pressure from the rollers when this is necessary, whether for the cleaning of the machine or simply for tying a broken roving, and likewise when, at the end of the week's work, all the machines have to be relieved of load, in order to obviate the rollers being damaged by remaining inactive and under pressure.

The mechanism forming the subject of this invention completely obviates these disadvantages, since in it the pressure is transmitted to the rollers from above without there being any pressure-transmitting member situated between the table of the machine and the rollers of the drawing mechanism, and without it being necessary to alter the usual construction of the top rollers and of the "cap bar neps" or grooved supporting frames in which the journals of these top rollers slide. As a result of this construction, the table of the machine remains completely free, and can always be kept clean without any difficulty.

Furthermore this mechanism enables the drawing rollers to be relieved at will with great facility, and in such a way that it is possible in a simple manner to unload and raise the front roller in order to tie a broken roving while still continuing the pressure on the other rollers; or alternatively all the rollers can be relieved simultaneously by raising, with a very easy movement, all their pressure members; and finally the cap bar neps or supporting frames of the top rollers can also be raised whenever this may

2

be necessary, either for the cleaning of the machine or for other purposes. In all these operations no levers, hooks, draw-rods or other detached parts remain, but the pressure mechanism, on relieving the rollers and rising, remains conveniently mounted on the machine, and by a simple rotary movement can return to resume its working position.

The mechanism according to this invention is characterised by the feature that all parts of the pressure mechanism are mounted above the bar which usually runs through the rear part of the machine, behind the rollers of the drawing mechanism, and which sustains the cap bar neps or supporting frames of the top rollers.

Upon this bar are mounted, according to the present invention, not only the frames supporting the top rollers, but also certain arms which carry the pressure mechanism, and a support which carries a helical spring, which is the member that produces the pressure that weighs down the rollers. Some of these members are rotatably mounted upon the bar, and retained by means of latches which can be released at the appropriate moment, and other members are permanently fixed to the bar and can oscillate rotationally jointly with the bar, which for this purpose is rotatably mounted upon bearings on the roller stands.

In the accompanying drawings the pressure mechanism according to this invention is illustrated by way of example as applied to a drawing mechanism for a continuous spinning machine. It could be applied in the same way to the mechanism on the rollers of a self-acting mule or of a flyer frame or other preparation machine.

Figure 1 of these drawings represents a section of the mechanisms by a plane perpendicular to the axes of the rollers; and

Figure 2 is a view from the rear of the mechanism, looking in the direction of the arrow II in Figure 1.

The apparatus illustrated by way of example in the drawings comprises four pairs of rollers, 1 and 2, 3 and 4, 5 and 6, and 7 and 8. The rollers 1, 3, 5 and 7 are actuated conveniently by the machine, the top rollers 2, 4 and 8 are weighted by the pressure mechanism forming the subject of this invention, and the top roller 6 is assumed to be a slipping roller of small diameter for accompanying the fibres.

The mechanism may comprise, in a manner already known, fibre-propelling members of any appropriate type between the rollers 3—4 and

the roller 5—6, or alternatively the rollers 5 and 6 may be omitted and these propelling members may be made to convey the fibres to the rollers 7 and 8.

Pressure is exerted upon the rollers by means of a pressure saddle formed by two parts 11 and 12 articulated to one another at the point 13. The part 11 weights the front roller 8, and includes in front the usual hook 14 for raising it when required, and the part 12 weights the two rear rollers 2 and 4.

According to the invention this double saddle 11, 12 receives pressure by means of a lever 15, which arranged above the rollers, is rockable about a pivot 16, and is articulated by its front end to the saddle 11 at 17. This lever in its turn receives pressure from a spring 18, which acts upon its rear end.

The pivot 16 of the lever 15 is mounted in the interior of a hollow arm 21, which is rockably mounted upon the rear bar 20 upon which the entire pressure mechanism is mounted. This bar 20 is parallel to the rollers, and is arranged in the rear part of the mechanism, mounted upon supports 22 fixed by means of screws 23 to the roller stands 10 of the machine.

Preferably this bar 20 is provided with a plane longitudinal face 24, which facilitates the fixing thereto of the various members that have to be mounted upon it simply by means of conical pins 25. The hollow arm 21 is mounted loose upon the bar 20, and between the two lateral walls of this arm is arranged a supporting block 26, which is fixed to the bar by means of a pin 25. This block is provided with a notch 27, in which engages a latch or catch 28, mounted upon the arm 21 and provided with a feeler button 29. In the position illustrated in the drawing the latch 28 is engaged in the notch 27, and the arm 21 remains rigidly united with the block 26, and therefore with the bar 20, but by depressing the feeler 29 the latch 28 is released, and then the arm 21 can swing upwards, raising with it the pressure lever 15 and the double saddle 11, 12, so that all the rollers are relieved of pressure.

The member 26, fixed, as has been stated, to the bar 20, is provided, in the interior of the arm 21, with a prolongation 30, in the interior of which is mounted the spring 18, which by means of a plunger 31 exerts pressure upon the rear end of the lever 15. The bar 20 also carries mounted thereon the cap bar neps or supporting frames of the top rollers, and to this end, between the two branches formed by the support 22 of the roller stand, is mounted, as shown in fuller detail in Figure 2, a member 32 fixed to the bar by means of a pressure screw 33, and having a prolongation 34 with a rod 35, upon which are mounted the supporting frames of the top rollers.

Finally the hollow arm 21 carries on its end a latch 36, which is close to a tooth 37 on the pressure saddle 11, for the purpose of keeping this saddle raised and thus relieving the front roller 8.

The bar 20 may be in one piece, which extends to the entire length of the machine, or may be divided into a number of sections, and carriers, fixed on each of these sections by means of a pin 25, a hoop 40 provided with a prolongation 41 carrying an adjustable abutment screw 42, which cooperates with a latch 43, which is so mounted upon the roller stand 10 as to be freely rotatable about a pivot 44, and is actuated by a dependent counterpoise 45. The assemblage is arranged in such manner that in the normal position, by

the action of this counterpoise 45, the latch 43 presses against the rear part of the roller stand as illustrated in Figure 1, and the abutment screw 42 prevents the bar 20 revolving. But when for any reason it is desired not only to relieve the pressure but to raise the supporting frames of the top rollers, after withdrawing these rollers the corresponding latch 43, 45 is rocked away from the screw 42, and the bar 20 can itself revolve, carrying round in its movement the frames 32, 34, 35 supporting the top rollers. This readily leaves the top rollers perfectly free whenever this is convenient, without dismantling the pressure mechanism.

With this pressure mechanism it is possible to relieve the front roller 8 by slightly raising the hook 14 until the tooth 37 is engaged by the latches 36. In this position the rollers 2 and 4 remain weighted. If it is desired to relieve all the rollers the finger 29 is depressed to release the latch 28, whereupon the arm 21 rises, and carries the pressure saddle up with it; and finally, if it is desired to raise the supports of the top rollers, the latch 43 is released, the bar 20 rotates, and the support 32, 34, 35, swings upwards with it.

I claim:

1. In a pressure mechanism for the rollers of spinning and preparation machines having a drawing mechanism mounted on a roller stand and rear bar mounted on said roller stand adjacent said drawing mechanism, an arm having one end rotatably mounted on said rear bar, said arm being located above the rollers, a lever pivoted intermediately of said arm, a pressure saddle for loading the rollers, one end of said lever being articulated to said pressure saddle, and a spring mounted on said rear bar actuating the other end of said lever in such a way that by raising the arm around its pivot and rotating it around the rear bar the saddle is likewise raised, and all the rollers are relieved, without having to relax or dismount the spring.

2. In a pressure mechanism as claimed in claim 1, a fixing latch on said arm adjacent with and cooperating with said rear bar, which, in the normal position, rigidly unites said arm with the rear bar, but readily permits disengagement thereof when the arm is to be raised.

3. In a pressure mechanism as claimed in claim 1, said pressure saddle comprising a front member articulated directly to the end of the lever on the arm and directly loading the front roller, and a rear member loading the rear rollers articulated to said front member, a tooth on said front member, a latch on the end of said arm adjacent said tooth, said tooth adapted to cooperate with said latch and permit said latch to engage said tooth to raise said front member of the saddle thereby unloading the front roller without unloading the rear rollers.

4. In a pressure mechanism as claimed in claim 1, a supporting block carried by said rear bar of the drawing mechanism rigidly fixed thereto, and forming a support for the pressure spring that acts for loading the rollers.

5. In a pressure mechanism as claimed in claim 1, a member carried by said rear bar rigidly fixed thereto, and supporting frames for all the top rollers of the mechanism carried by said member.

6. In a pressure mechanism as claimed in claim 1, said rear bar being rotatably mounted upon the roller stands, an abutment arm carried by said rear bar and fixed thereto, a thrust latch

mounted on said roller stand normally pressed by said abutment arm for preventing rotation of the bar, and whereby upon raising said thrust latch said bar can be rotated and said arm can be raised with the entire pressure mechanism 5 and the supporting frames for the top rollers.
